CLAIM

The ornamental design for a lexington raised pattern garage door panel, as shown and described.

DESCRIPTION

FIG. 1 is an enlarged front elevational view of a garage door panel of the lexington raised pattern garage door panel of FIG. 7;

FIG. 2 is a top plan view of the lexington raised pattern garage door panel of FIG. 7;

FIG. 3 is a bottom plan view of the lexington raised pattern garage door panel of FIG. 7;

FIG. 4 is a right side elevational view of the lexington raised pattern garage door panel of FIG. 7;

FIG. 5 is a left side elevational view of the lexington raised pattern garage door panel of FIG. 7;

FIG. 6 is an enlarged sectional view of the lexington raised pattern garage door panel of FIG. 7 along view 6—6 of FIG. 1; and,

FIG. 7 is front elevational view of the lexington raised pattern garage door panel incorporating the garage door panel of FIGS. 1—6.
